UNITED STATES PATENT OFFICE.

WILLIAM W. STERLING, OF JEROME, ARIZONA.

DEVICE FOR IMPELLING ROTARY FLYING TOYS.

1,334,184.

Specification of Letters Patent. Patented Mar. 16, 1920.

Application filed August 18, 1919. Serial No. 318,216.

To all whom it may concern:

Be it known that I, WILLIAM W. STERLING, a citizen of the United States, residing at Jerome, in the county of Yavapai and State of Arizona, have invented new and useful Improvements in Devices for Impelling Rotary Flying Toys, of which the following is a specification.

The object of my present invention is the provision of a peculiar and advantageous device in the nature of a toy, and adapted to be used for the impelling of rotary flying toys.

To the attainment of the foregoing, the invention consists in the novel construction and adaptation of parts as hereinafter described and definitely claimed.

In the accompanying drawings, hereby made a part hereof:

Figure 1 is a side elevation of my novel device.

Fig. 2 is a longitudinal section of the same. Fig. 3 is a transverse section taken in the plane indicated by the line 3-3 of Fig. 2.

Similar numerals of reference designate corresponding parts in all of the views of the drawings.

My novel device is preferably formed with a view to simulating a pistol of the revolver type, and among other elements it includes a hand-grip 1, and a portion 2 that extends forwardly from and is preferably integral with the hand grip.

Socketed in and connected by a wood screw 3 or other means to the body portion 2, is a longitudinal spindle 4, and fixed to and disposed in front of the body portion 2 is a casing 5 which receives in its center the intermediate portion of the spindle 4.

Pivoted at 6 to the spindle 4 and adapted to be moved in a slot 7 in the casing 5 is a trigger lever 8 that is subject to a retractile spring 9 and is provided with a forwardly extending sear 10.

It will be noted that the spindle 4, the trigger 8 and the spring 9 are all connected to the body portion 2 by the simple operation of turning the wood-screw end 3 of the spindle 4 into said body portion 2, which contributes materially to the inexpensiveness of the device.

Journalized in the casing 5 and on the forward portion of the spindle 4, and projecting forwardly from the casing 5 so as to simulate the barrel of a pistol, is a tubular rotary member 11 having on its forward end and off its center a forwardly projecting pin 12. In the tubular member 11 is housed a spring 13 that is coiled about the spindle 4 and is connected at 14 to said spindle, and at 15 to the tubular member. At the rear end of the tubular member 11 is carried a ratchet disk 16 that is fixed with respect to the said member 11 and is arranged in the same plane as the before-mentioned sear 10. 65

The tubular member 11 is revoluble about the spindle 4, and when it is turned in one direction, the spring 13 will be placed under tension and will be retained in such state by the co-operation of the sear 10 with the ratchet disk 16. Then when the trigger lever 8 is pulled to disengage the sear 10 from the ratchet disk 16, the spring 13 will operate to powerfully rotate the tubular member 11. 75

It will be apparent from the foregoing that my novel device may be used to advantage for impelling through the air that type of well known rotary flying toy that is provided with a central aperture and an aperture adjacent to but off its center, the forward portion of the spindle 4 being designed to be placed in the central aperture of the toy and the pin 13 in the other aperture thereof, so that when the member 11 is rapidly rotated in the manner described, the toy will be caused to rise in and fly through the air. 80

It will also be apparent that notwithstanding the simplicity of its construction, 90 my novel device is adapted to afford considerable amusement to a child.

Having described my invention, what I claim and desire to secure by Letters-Patent, is:

A device for the purpose described, comprising a body, a casing fixed with respect to the forward portion of the body, a spindle having a rear wood-screw end portion embedded in and fixed of itself to the body, 100 said spindle extending forwardly through and beyond the casing, a tubular revoluble

member having its rear portion disposed in the casing and equipped with a ratchet disk and also having its forward end spaced rearwardly from the forward end of the spindle and provided off its center with a projection, a spring housed in the tubular member, and a trigger lever subject to the action of spring

and pivoted to the spindle and adapted to play in an opening in the wall of the casing and having a sear positioned to normally co- 10 operate with the ratchet disk in holding the tubular member against rotation.

In testimony whereof I affix my signature.
WILLIAM W. STERLING.
